UNITED STATES PATENT OFFICE.

PETER SMITH, OF NEWARK, NEW JERSEY.

COVER DEVICE FOR BARRELS AND THE LIKE.

Application filed November 5, 1921. Serial No. 513,123.

To all whom it may concern:

Be it known that I, PETER SMITH, a citizen of the United States, residing at Newark, in the county of Essex and State of New Jersey, have invented certain new and useful Improvements in Cover Devices for Barrels and the like, of which the following is a specification.

This invention relates particularly to removable cover devices for barrels and the like receptacles into which dusty substances, such as ashes, are to be shovelled and which have an upright cowl with a lateral opening therein and a pendant swinging damper 10 or door which normally closes the opening and is adapted to be pushed away from the same by the shovel to admit the contents of the latter.

According to my invention the device is formed with a cowl which as to its major upper portion is substantially rectangular in plan, thus to substantially conform with the contour of the bowl of an ordinary shovel entered into the cowl through a lateral opening therein, and which as to its lower portion is formed funnel-shaped; and with a base-plate (preferably having a downward circumferential rim or flange) which has a relatively limited aperture into which the base of the funnel-shaped part of the cowl is fitted. Thus, while the aperture may be made quite small relatively to the diameter of the base-plate, thereby to adapt the device to a wide range in diameters of barrels, the cowl is formed to receive without interference a considerable part of the shovel bowl and so facilitate the discharge, without spilling, of the contents of the shovel into the cowl.

Further, the damper is peculiarly formed and supported. That is to say, given the mouth or receiving opening in the upright wall of a body structure (as the cowl), the damper is formed of a plate pivoted within said structure on a horizontal axis at the upper part of the plate and near the inner face of the wall, said plate being bent so that its upper portion is pitched upwardly, and the remainder or lower portion thereof is pitched downwardly, toward said wall; thus the center of gravity of the damper is back of its pivoting axis and the damper is self-closing. Preferably the said lower portion of the damper is planiform and represents its major part, so that the shovel will obtain an unobstructed sliding contact there-

with, to open the same, when it is thrust into the cowl mouth. Preferably, also, the plate forming the damper has lateral forward flanges which act principally to stiffen it.

In the drawing,

Figure 1 is a front elevation of the device, a portion thereof being shown broken away;

Figure 2 is a view showing the device 65 mainly in vertical section and in place on a barrel; and

Figure 3 is a plan showing the cowl in horizontal section.

The device is formed for the most part 70 of sheet metal. A designates the base plate and B the cowl.

The base plate is formed by a disk *a* having a depending flange or rim *b* and also having a central circular aperture *c*. The 75 opening is small relatively to the diameter of the disk *a* so that the base plate may rest on barrels which range widely in diameter. The base plate is shown resting on a barrel in Fig. 2, which is indicated at C. 80

The cowl *B* has its major upper portion substantially rectangular in plan and its lower portion funnel-shaped and is constructed as follows: Its body portion is formed of four sheets *d e e'* and *f*. The 85 sheet *d* is in the blank substantially rectangular. The sheets *e e'* are also substantially rectangular excepting that one corner of each is removed and each sheet is formed with a curved edge *e²*. The sheet *f* is also 90 substantially rectangular. The sheets *e e'* form the side walls of the body structure and the sheet *d* forms the back thereof, the latter lying from the horizontal plane marked *g g* in Fig. 2 upwardly in contact with the 95 back edges, the curved edges *e²* and the top edges of the sheets *e e'* and having its lateral edges from said plane *g g* upwardly bent off as angular flanges *e³* which are soldered to the sheets *e e'*. The upper edge 100 portion *d'* of the sheet *d* extends beyond the front edges of the sheets *e e'*, which latter have forward flanges *e⁴*, and the flange *d'* is bent downwardly and the flanges *e⁴* inwardly in perpendicular relation to the respective walls *d* and *e e'*, the flanges *e⁴ e⁴* being overlapped by and riveted to the flange *d'*, as at *h*. The upper edge portion 105 of the sheet *f* is overlapped by the lower ends of the flanges *e⁴* and riveted thereto, 110 as at *i*. Thus the flanges *d'* and wall *f* form the mouth or opening of the cowl,

- the same being rectangular in form. Below the plane g g is the funnel-shaped portion of the cowl, the same being formed by suitably overlapping the lateral edge portions of the wall f and the lateral lower edge portions of the wall d with respect to the forward and rearward lower edge portions of the sheets e e' , the thus lapped portions being secured together by rivets h .
- 10 The cowl B is secured on the base plate A by turning downwardly the edge a' of the latter around the aperture c therein, fitting the lower edge of the funnel-shaped portion of the cowl into the aperture and then folding the edge of the funnel-shaped portion back on the edge of the aperture; if desired the seam thus formed may also be soldered.
- 15 Thus while the base of the device is adapted to various sizes of barrels, its aperture c being formed as small as necessary for that purpose, the upper part of the cowl is not only of ample size but of proper shape to conform with the plan of a shovel bowl thrust thereinto through its mouth j , which
- 20 is desirable in order to avoid disturbing and possibly spilling the ashes outside of the cowl.

For keeping the dust from flying about the cowl is provided with a self-closing damper or door constructed and arranged as follows: There is a horizontal pivot bar l arranged in the walls e e' above the opening j and close to the front wall of the cowl formed by d' e' e' and f . Pivoted in pendent relation to this bar is the damper m . This damper is formed by a sheet or plate which is bent so that its upper portion m' is pitched upwardly, and the remainder or lower portion m^2 is pitched downwardly, toward said front wall; in the preferred construction the portion m^2 represents the major portion of the damper and it and the portion m' are planiform, so that an angle exists at m^2 . Also in the preferred construction portions m' and m^2 have in the blank lateral wings m^4 and m^5 which are bent forward into perpendicular relation to said portions, the flanges m^4 and m^5 at each side of the damper overlapping each other and being secured together by a rivet m^6 . These flanges have a front rectilineal edge m^7 . The pivot of the damper on the pin l may be formed by bending the upper edge of the sheet m around the pin, as at m^8 . The lower edge of the sheet forming the damper may be turned off, as at m^9 to bear flatwise against the upper edge of the sheet f which is shown bent downwardly and inwardly at an incline, as at f' in Fig. 2. n is a handle or bail attached to the top of the wall d of the cowl.

It will be understood that in use the user thrusts the loaded shovel bowl against the damper and into the cowl, the damper swinging back, the shovel being then tilted to allow its contents to fall into the barrel;

whereupon on removal of the shovel the damper resumes its closed position (shown by full lines in Fig. 2) because on account of its described construction its center of gravity is back of the pivot l . By forming the lower downwardly and forwardly pitched portion of the damper planiform and making it the major portion of the damper the shovel has an unobstructed sliding contact therewith.

Having thus fully described my invention, what I claim as new and desire to secure by Letters Patent is:—

1. A sheet-metal cover device including, in combination, a base-plate having an aperture therein, and a cowl upstanding from the base-plate and having the major upper portion thereof rectangular in plan and the lower portion thereof funnel-shaped and fitted at its base to the aperture in the base-plate, said upper portion having a lateral opening approximating in width and height the width and height of said major upper portion of the cowl.

2. A sheet-metal cover device including, in combination, with a base-plate having an aperture therein, a cowl, said cowl including upstanding opposite side walls having back, top, bottom and front edges, a third upstanding wall joined to the back edges of the side walls and extending over the latter forwardly and joined to their top edges, said side walls having frontal inturned flanges extending approximately from their top edges to points short of their bottom edges and the top wall having a downturned frontal flange overlapping and secured to the other flanges, a fourth upstanding wall having its top portion secured to the lower ends of the flanges of the side walls and forming with said flanges and the said flange of the third wall the mouth of the cowl, the lower portions of said side walls forming with the fourth wall and the lower portion of the third wall a funnel-shaped cowl base and having their lateral portions overlapping and secured to lateral portions of said third and fourth walls, and the lower edge of the cowl base being secured to the base plate around the aperture therein.

3. In combination, with a body structure having an upright wall formed with a receiving opening therein, a substantially rectangular plate forming a damper for the opening and arranged wholly within said structure and pivoted therein on a horizontal axis parallel with one edge of the plate and near the inner face of said wall, said plate being bent so that its upper portion is pitched upwardly, and the remainder thereof pitched downwardly, toward said wall, and said plate having lateral upright flanges extending from substantially top to bottom thereof and reaching from said portions toward said wall and having its top and bottom edges

and the forward edges of said flanges close to the inner face of said wall.

4. In combination, with a body structure having an upright wall formed with a receiving opening therein, a substantially rectangular plate forming a damper for the opening and pivoted in said structure on a horizontal axis parallel with one edge of the plate, said plate being bent so that its upper

portion is pitched upwardly and outwardly 10 and the remainder thereof pitched downwardly and outwardly, and the portions above and below the bend having lateral outwardly projecting flanges at both sides thereof, the flanges at each side overlapping 15 each other and being secured together.

In testimony whereof I affix my signature.

PETER SMITH.
